SOOT COLLECTOR

William Nulle, Aberdeen, S. Dak.

Application November 10, 1936, Serial No. 110,151

2 Claims. (Cl. 126—280)

This invention relates to a novel furnace and/or boiler accessory such as may be conveniently referred to as a dust and soot collector or depository.

5 Needless to say, I am sufficiently conversant with the prior state of the art to realize that soot traps and equivalent devices have been constructed for use in association with smoke stack conduits and piping in general. In other words, 10 I appreciate that it is broadly old to provide accessible means whereby soot can be brushed from the stack pipe into a collector or receptacle and thereafter disposed of.

It follows, therefore, that the present invention constitutes what is believed to be an improvement on known prior art and marketed devices in this same line of endeavor. It is characterized by simplicity, practicability, efficiency in operation and is structurally distinct, by way 20 of contrast with known structures, in that it includes unusual telescopic receptacle equipped means to take care of the dislodged soot.

In reducing the inventive idea to practice I have devised a substantially dust-proof structure 25 wherein the receptacle portion thereof rests directly on the floor to relieve the stack of the hanging weight of the attachment.

Other features and advantages will become more readily apparent from the following description and drawing.

30 In the drawing:—

Figure 1 is an elevational view showing the complete assembly including a part of the stack, a furnace, and the improved soot collector interposed between the stack and the discharge nipple on the back of the furnace.

Figure 2 is an enlarged central vertical view on the line 2—2 of Figure 1.

Figure 3 is a horizontal section on the line 3—3 40 of Figure 2.

In the drawing, in Figure 4 the numeral 4 designates any suitable type of a furnace, boiler, or the like. On the back is the customary attaching nipple or neck 5 to accommodate the smoke stack pipe or conduit 6. In accordance with the present invention a T-shaped adapter union or coupling is interposed between the features 5 and 6. The main part of the coupling is indicated at 7 and the depending part 8 is turned down to accommodate a delivery tube or pipe 9. This is in effect a saddle and is placed over the T-coupling and the free ends of the arms thereof terminate in hooks 11 engaged with eyes 12 on the ends of a connecting and hanger link or rod 13 carried by the upper end portion of the soot and dirt delivery pipe 60 or tube 9. The lower end of the part 9 fits tele-

scopically into an elongated receptacle or cup 14 and the two features 9 and 14 are thus extensible to permit the collector to be interposed between the floor 15 and the T-coupling or other connecting means on the stack 6. That is to say, 5 these features cooperate to render the device self-adapting whereby the charged cup or receptacle 14 may rest directly on the floor to relieve the stack 6 of a hanging weight such as is sometimes found to be evident in prior art devices. 10

It will be noted that the T-coupling is as close as possible to the furnace. This puts it in a position to enable a brush or reach implement (not shown) to be placed in the top of the furnace to literally dust the soot into the receptacle 14 15 by way of the delivery pipe or connection 9.

Novelty is predicated upon the idea of resting the cup 14 directly on the floor 15 and affording adjustable communicating connection between it and the stack 6. Then too, the specific T-coupling and connecting pipe 9 cooperating with the cup 14 is believed to be an ingenious adaptation in this particular line of endeavor. Additional novelty appears to reside in the saddle-like retainer 10 having hooked releasable connection 25 with the eyes 12 on the ends of the connecting link 13, thus affording a novel separable connection between the T-coupling 7 and the delivery pipe 9.

It is thought that the description taken in 30 connection with the drawing will enable a clear understanding of the invention to be had. Therefore, a more lengthy description is thought unnecessary.

While the preferred embodiment of the invention has been shown and described, it is to be understood that minor changes coming within the field of invention claimed may be resorted to if desired.

What is claimed is:—

1. A soot collector of the class described comprising a T-coupling, a delivery pipe attached to the short branch or stem of said coupling, a cylindrical cup constituting a receptacle, said pipe having one end fitting telescopically into said receptacle, a saddle bridging the T-coupling, a pin carried by the adjacent end portion of said pipe, said pin terminating in eyes, said saddle having its end portions terminating in hooks releasably engageable with said eyes. 45

2. The combination with the smoke pipe of a furnace, of a coupling disposed in the line of said pipe, a pipe-like receptacle having a closed end adapted to rest on the floor, a pipe connection between said coupling and receptacle telescoping 55 at one end into the open end of the receptacle, and a saddle member spanning said coupling and detachably attached to said pipe connection.
